(57) **ABSTRACT**

The present invention relates to a radio frequency antenna (10) including an antenna array (12) operating at one wavelength and comprising:

a powered dipole (14A) connected at an access point (15) to a radio frequency transmitter generating or receiving a wave at the wavelength, at least one coupled dipole (14C1, 14C2, 14C3) connected at an access point to a respective load (Z1, Z2, Z3), the powered dipole (14A) and each coupled dipole (14C1, 14C2, 14C3) including two strands extending from the access point (15), the access points (15) being arranged so as to form a polygon, the first strand of a dipole (14)

(Continued)

extending along the second strand of a neighboring dipole (14) at a distance less than one tenth of the wavelength.

RADIOFREQUENCY PLANAR ANTENNA
WITH CIRCULAR POLARISATION

This patent application claims the benefit of document FR 21/14072 filed on Dec. 21, 2021, which is hereby incorporated by reference.

The present invention relates to a radio frequency antenna. The present invention further relates to a system including such a radio frequency antenna.

The technical field is that of radio frequency antennas, and more specifically circularly polarized antennas.

Circularly polarized radio frequency waves are used in particular, in satellite communications insofar as circular polarization makes it possible not to depend on the orientation alignment between the satellite and the receiver.

As an example of a particular application, the case of the GPS system can be cited. "GPS" is the acronym of "Global Positioning System". Such a system operates with circularly polarized waves the frequencies of which are either 1225 MHz or 1575 MHz.

According to another example of application, for constellations of microsatellites in low orbit, communications are made using circularly polarized waves the frequencies of which are either 400 MHz or 868 MHz.

A plurality of antenna systems for obtaining circularly polarized waves have been developed.

So-called microstrip antennas are known antennas associated with dual excitation circuits for obtaining circular polarization by combining the two orthogonal modes. In some embodiments, a plurality of superimposed patches is used for obtaining a plurality of operating frequency bands.

Other antenna systems use quadrifilar helical antennas associated with quadruple excitation circuits.

There are also crossed dipoles associated with double excitation circuits. In some particular cases, to facilitate integration, the radiating elements used are miniaturized.

In each case, circularly polarized antennas consist of a plurality of radiating elements associated with a specific excitation circuit. The excitation circuit makes it possible to establish amplitude and phase weighted excitations of the different radiating elements.

However, antennas produced in this way have a relatively large overall size.

There is thus a need for an antenna apt to emit circularly polarized radio frequency waves and which has a reduced bulk.

To this end, the description describes a radio frequency antenna comprising at least one antenna array operating at an operating frequency, each antenna array comprising a powered dipole, the powered dipole being connected at an access point, to a radio frequency transmitter suitable for generating or receiving a wave at the operating frequency. Each antenna array further comprises at least one coupled dipole, each coupled dipole being connected at an access point to a respective resistive and/or capacitive and/or inductive load. The powered dipole and each coupled dipole comprise two strands, the strands extending from the access point, the access points being arranged so as to form a polygon, the first strand of a dipole extending along the second strand of a neighboring dipole on said polygon at a distance less than or equal to one tenth of the wavelength corresponding to the operating frequency, said wavelength being called operating length.

According to other particular embodiments, the antenna has one or a plurality of the following features, taken individually or according to all technically possible combinations:

2

both strands have a length less than or equal to a quarter of the operating wavelength.

the first strand of a dipole extends along the second strand of a neighboring dipole on said polygon at a distance less than or equal to one twentieth of the operating wavelength.

a direction being defined for each strand, the directions of the two strands have an angle therebetween equal to 90° to within plus or minus 10%, the powered dipole and each coupled dipole being arranged so that each direction of one strand intersects with a direction of another strand.

the polygon is a regular polygon.

the number of coupled dipoles of an antenna array is comprised between 2 and 4.

the radio frequency antenna includes two antenna arrays, the polygon formed by the access points of the second antenna array being included in the internal space delimited by the polygon formed by the access points of the first antenna array, each antenna array operating at a respective operating frequency.

the radio frequency antenna has a reflector plane located at a distance less than or equal to one quarter of the operating wavelength.

the strands have meanders or folds.

the loads of the coupled dipoles are chosen so that:

the radiation from the radio frequency antenna has a right circular polarization with a maximum gain along the direction perpendicular to the radio frequency antenna,

the radiation from the radio frequency antenna has a uniform right circular polarization for an elevation aperture between 90° and -90° around the direction perpendicular to the radio frequency antenna, and the gain of the cross polarization is minimized.

The description further relates to a system, in particular a satellite positioning system, including at least one radio frequency antenna as described above.

The features and advantages of the invention will appear upon reading the following description, given only as an example, but not limited to, and making reference to the enclosed drawings, wherein:

FIG. 1 is a schematic representation of an example of an antenna,

FIG. 2 is a schematic representation of a perspective view of the antenna shown in FIG. 1,

FIGS. 3 and 4 are simulation graphs showing the performance obtained with the antenna shown in FIG. 1,

FIG. 5 is a schematic representation of another example of an antenna,

FIGS. 6 to 8 are simulation graphs showing the performances obtained with the antenna shown in FIG. 5,

FIG. 9 is a simplified representation of examples of antenna arrangement, and

FIG. 10 is a simplified representation of other examples of antenna arrangement

Before describing in a general way, the antenna forming the subject matter of the present invention, the present description is concerned with describing two particular examples.

The two particular examples are applied to the case of a GPS system.

The first example relates to the band L1 and the second to a double band L1/L2.

The frequency band L1 is a relatively narrow band around the central frequency of 1575 MHz. In such context, the term

"narrow" means a frequency extension on the order of less than 5% of the central frequency.

Similarly, the frequency band L2 is a relatively narrow band around the central frequency of 1225 MHz.

EXAMPLE 1: ANTENNA FOR THE BAND L1

A radio frequency antenna 10 is illustrated schematically in FIG. 1.

The antenna 10 is suitable for operating at a central operating frequency f_0 . The associated wavelength is referred to as the central wavelength λ_0 .

The central operating frequency f_0 is 1575 MHz for the first example.

The antenna 10 includes an antenna array 12, the antenna array 12 being herein, as will subsequently be explained, an array of nested antennas.

Furthermore, the antenna 10 is a planar antenna for which a first longitudinal direction corresponding to an axis X (height of the sheet on which FIG. 1 is shown) can be defined and the second strand 18A extends along a second longitudinal direction corresponding to an axis Y (width of the sheet on which FIG. 1 is shown).

In the example shown in FIG. 1, the antenna array 12 is formed by four elementary dipole antennas, simply named dipoles 14 hereinafter.

Each dipole 14 has an L-shaped structure.

As can be seen in FIG. 1, each dipole 14 has an access point 15 and two strands 16 and 18.

The access point 15 is a contact positioned in the center of the dipole 14 and connected to one end of the two strands 16 and 18.

It can be noted that the 15 access points form a square.

The two strands 16 and 18 preferentially have the same length, the length advantageously being less than or equal to $\lambda_0/4$, so that each dipole 14 is a half-wave element.

Furthermore, the angle between each strand 16 and 18 is equal to 90°.

A general L-shape is thus obtained.

Furthermore, each strand 16 and 18 is connected to an access point 15 which is connected either to a source or to a load.

More precisely, a dipole 14 is supplied at the center thereof by a radio frequency source suitable for generating a wave at the operating frequency f_0 .

Hereinafter, the corresponding dipole 14 is called "powered dipole 14A".

In the example shown in FIG. 1, the first strand of the powered dipole 14A is denoted as first strand 16A and the second strand of the powered dipole 14A is denoted as second strand 18A.

The first strand 16A extends along the first longitudinal direction X and the second strand 18A extends along the second direction Y.

In general, the first strand 16 of a dipole 14 is closer to the inside of the antenna than the second strand 18. The first strand 16 could thus be called "inner strand" whereas the second strand 18 could thus be called "outer strand". The inside and the outside are defined herein in relation to the square formed by the access points: the closer an element is to the center of the square, the more the center is inside.

Thus, depending on the case, the first strand 16 of a dipole 14 extends either along the first longitudinal direction X or along the second longitudinal direction Y, the second strand 18 extending along the other direction.

The other dipoles 14 include a center corresponding to an access point connected to a respective complex load Z. The

respective load can be a resistive, a capacitive and/or an inductive load. Each of the strands 16 and 18 of the dipoles 14 has an end which is connected to the access point 15 of the dipole 14 to which the strand 16 and 18 belongs, thus allowing each strand 16 and 18 to be connected to the load specific to the dipole 14 considered.

Hereinafter, each of the corresponding dipoles is called "coupled dipole 14C".

In such a case, the antenna 10 shown in FIG. 1 includes a powered dipole 14A and three coupled dipoles 14C.

Thereafter, the coupled dipoles 14C are ordered (first 14C1, second 14C2 and third 14C3, respectively) according to a counterclockwise order. The reference signs of the strands 16 and 18 of a coupled dipole 14C have the same suffix as the coupled dipole 14C to which the strands belong. Thus, the first strand of the first coupled dipole 14C1 has the reference sign 16C1 and the second strand of the first coupled dipole 14C1 has the reference sign 18C1.

The dipoles 14 are arranged moreover in a specific manner, so as to allow a coupling therebetween.

More precisely, as indicated above, in the case of FIG. 1, the access points 15 form a square.

Moreover, each first strand 16 of a dipole 14 is parallel to a second strand 18 of another dipole 14.

Thus, the first strand 16A of the powered dipole 14A is inside and parallel to the second strand 18C1 of the first coupled dipole 14C1 whereas the second strand 18A of the powered dipole 14A is outside and parallel to the first strand 16C3 of the third coupled dipole 14C3.

The first strand 16C1 of the first coupled dipole 14C1 is outside and parallel to the second strand 18C2 of the second coupled dipole 14C2 whereas the second strand 18C1 of the first coupled dipole 14C1 is outside and parallel to the first strand 16A of the powered dipole 14A.

The first strand 16C2 of the second coupled dipole 14C2 is inside and parallel to the second strand 18C3 of the third coupled dipole 14C3 whereas the second strand 18C2 of the second coupled dipole 14C2 is outside and parallel to the first strand 16C1 of the first coupled dipole 14C1.

The first strand 16C3 of the third coupled dipole 14C3 is inside and parallel to the second strand 18A of the powered dipole 14A whereas the second strand 18C3 of the third coupled dipole 14C3 is outside and parallel to the first strand 16C2 of the second coupled dipole 14C2.

Such arrangement allows the dipoles 14 to be interlaced, allowing the dipoles 14 to couple with each other due to the proximity thereof and because some strands 16 and 18 are collinear with each other.

In fact, in such arrangement, the distance between two points of two collinear strands 16 and 18 is relatively small for good coupling.

As an example, the distance between two collinear strands 16 and 18 is less than or equal to $\lambda_0/10$.

Preferentially, the distance between two collinear strands 16 and 18 is less than or equal to $\lambda_0/20$.

The interleaving of the dipoles 14 can be further used for a miniaturization of the antenna 10 since the antenna 10 has a width and a length on the order of $\lambda_0/4$.

In the present case, the antenna 10 has a width and a length of 5 cm.

In the case shown in FIG. 1, the powered dipole 14A is connected to the GPS reception system.

The first coupled dipole 14C1 is connected to a first capacitive load Z1 of 2.2 pF, the second coupled dipole 14C2 is connected to a second inductive load Z2 of 11.7 nH and the third coupled dipole 14C3 to a third inductive load Z3 of 0.7 nH.

In order to physically produce such an antenna **10**, the antenna is etched on a printed circuit onto which the components used for charging the coupled dipoles can be soldered. The antenna **10** is connected to the reception system e.g. through a microwave coaxial cable.

In such a case, the impedance values of the loads **Z1**, **Z2** and **Z3** have been adapted so as to obtain circularly polarized radiation.

More precisely, the impedance values of the loads **Z1**, **Z2** and **Z3** are chosen so that the radiation satisfies a plurality of conditions, namely:

- a first condition according to which the radiation has a right circular polarization (such a polarization is often called RHCP, an abbreviation for “right-handed circular polarization”) with a maximum gain along the zenith direction (corresponds to a direction **Z** perpendicular to the two longitudinal directions **X** and **Y**),
- a second condition according to which the radiation has a relatively uniform RHCP gain for an elevation aperture of $+/-90^\circ$ around said direction (covering the sky, upper half-sphere), and
- a third condition according to which the gain of the cross polarization (i.e. the gain of the left polarization or LHCP, abbreviation for “left-handed circular polarization”) is minimized.

Satisfying such conditions makes it possible to make the antenna **10** suitable for an application to a satellite positioning system. Such a positioning system is a system often referred to as GNSS. The abbreviation GNSS is the abbreviation for “global navigation satellite system”.

In order to determine appropriate load values **Z1**, **Z2** and **Z3**, a determination technique e.g. as described in U.S. Pat. No. 9,917,376 B2 can be used by resorting to a decomposition of the desired radiation on a spherical basis, an expression of the electromagnetic field generated by the antenna on the same basis, and a resolution of the equation resulting from the fact that it is desired that the two are identical.

It should be noted that the determination technique is all the easier to implement as the strands **16** and **18** are arranged to form a symmetrical dipole **14**.

From a hardware point of view, the loads **Z1**, **Z2** and **Z3** can be physical components.

Preferentially, in order to reduce the losses associated with the discrete component packaging, the loads **Z1**, **Z2** and **Z3** are produced by etching specific patterns. A spiral or an interdigitated capacitor are examples of such patterns.

As shown schematically in FIG. 2, the antenna **10** is placed above a reflective metal ground plane **20** with a side length of 25 cm in order to direct the radiation into the upper half-space.

According to the example described, the distance between the antenna **10** and the ground plane **20** is 25 mm, i.e. one eighth of a central wavelength λ_0 , so as to constructively reflect the radiation from the antenna along the direction of interest. Such an effect is obtained as soon as the distance between the antenna **10** and the ground plane **20** is less than a quarter of the central wavelength λ_0 .

In a variant, instead of the ground plane **20**, an artificial magnetic conductor is used. Such an element is often referred to by the abbreviation AMC (artificial magnetic conductor). In such a case, the distance from the antenna **10** can be even smaller, which reduces the overall height.

The performance of the antenna **10** described hereinabove are illustrated by the FIGS. 3 and 4.

FIG. 3 illustrates the gain diagram obtained at 1575 MHz along a first section plane orthogonal to the first longitudinal

direction **X** (shown with dotted lines) and along a second section plane orthogonal to the second longitudinal direction **Y** (shown with dot-dash lines). Moreover, the curves for the RHCP gain appear are shown with thicker line than the curves for the LHCP gain.

The observation of the gain diagram shows that the RHCP gain is optimized over the upper half-space and that the LHCP gain is minimized, which indeed corresponds to the desired conditions.

FIG. 4 shows the radiation properties along the zenith direction by representing the gain of the antenna **10** as a function of frequency.

In said curve, the first solid line curve is the gain LHCP expressed in dBic, the second solid line curve is the gain RHCP expressed in dBic and the third dashed line curve corresponds to the axial ratio expressed in dB.

The axial ratio can be used for measuring the polarization purity of the wave emitted by the antenna **10**. The axial ratio is the ratio between the major axis and the minor axis which form the ellipse describing the path of the wave. When the long and short axes of the ellipse are equal, the ratio is equal to 1, or 0 dB. In such case, the polarization of the wave is called circular. In practice, a wave is considered to be circularly polarized when the axial ratio is less than 3 dB.

The FIG. 4 shows that the RHCP gain at the desired frequency of 1575 MHz is enhanced, the LHCP gain having a minimum at 1575 MHz.

The analysis of the third curve shows that the axial ratio remains below 3 dB, which confirms a good purity of circular polarization at the desired frequency.

In the first example, the radiation of the antenna **10** is optimized without using a complex and expensive excitation circuit, due to the implementation of load components **Z1**, **Z2** and **Z3** with optimized values on the coupled dipoles **14C**.

Furthermore, the antenna **10** can be printed on a flat substrate, reducing the bulk and facilitating the integration into any system.

It can be noted that such arrangement has the advantage of operating on different frequency bands by means of a geometrical homothetic transformation and a recalculation of the loads.

EXAMPLE 2: ANTENNA FOR THE BANDS **L1** AND **L2**

The antenna **10** according to the second example is shown schematically in FIG. 5.

The antenna **10** has two antenna arrays **12_1** and **12_2**.

The first antenna array **12_1** has a shape similar to the antenna array **12** shown in FIG. 1.

However, same is dimensioned for operating on the frequency band **L2** and more specifically around the 1225 MHz central frequency.

In such case, the first coupled dipole **14C1** is connected to a first capacitive load **Z1** of 0.5 pF, the second coupled dipole **14C2** is connected to a second resistive load **Z2** of 1 M Ω and the third coupled dipole **14C3** is connected to a third capacitive load **Z3** of 3.3 pF.

The second antenna array **12_2** has the same architecture as the antenna array **12** shown in FIG. 1.

However, the powered dipole **14A** is replaced by a coupled dipole **14C**, so that the second antenna array **12_2** includes four coupled dipoles **14C**.

By referencing the dipoles similar to the case of the first antenna array **12_1** by continuing the numbering, the second antenna array **12_2** includes:

- a fourth coupled dipole **14C4** near the powered dipole **14A** which is connected to a fourth capacitive load **Z4** of 1.8 pF,
- a fifth coupled dipole **14C5** near the first coupled dipole **14C1** which is connected to a fifth capacitive load **Z5** of 0.5 pF,
- a sixth coupled dipole **14C6** near the second coupled dipole **14C2** which is connected to a sixth inductive load **Z6** of 24 nH, and
- a seventh coupled dipole **14C7** near the third coupled dipole **14C3** which is connected to a seventh capacitive load **Z7** of 22 pF.

In such case, the impedance values of the loads **Z1** to **Z7** have been chosen so as to obtain circularly polarized radiation in both frequency bands.

More precisely, the values of the impedances of the loads **Z1** to **Z7** are chosen so that the radiation satisfies the same three conditions as for the first example, but for the two frequency bands **L1** and **L2**.

From a practical point of view, the dimensions of the antenna **10** are 8 cm by 8 cm. The antenna **10** is printed by lithography (copper etching on dielectric substrate)

FIGS. 6 to 8 show the performance obtained with the antenna **10** according to the second example.

FIG. 6 shows two curves, a first curve **C1** with solid line representing the evolution with frequency of the gain of the antenna for a right circular polarization along the direction of the zenith (along the **Z** axis) and a second curve **C2** with dotted line illustrating the variation of the axial ratio with the frequency.

It appears that the gain is well optimized for the two aforementioned frequencies of 1225 MHz and 1575 MHz.

With the second curve **C2** of FIG. 6, it can also be seen that the axial ratio is minimized on the bands **L1** and **L2**. Satellite signals are received in this way at different frequencies used to improve the precision of geolocation by signal processing.

FIGS. 7 and 8 show the radiation patterns in two different cross-sectional planes, for each polarization. FIG. 7 corresponds to the frequency of 1225 MHz (band **L2**) whereas FIG. 8 corresponds to the frequency of 1575 MHz (band **L1**).

In each case, it is observed that the RHCP gain in the upper half-sphere is enhanced and that the LHCP gain is minimized.

The adapted optimization of the **Z1** to **Z7** loads associated with the double L-shaped dipole array **12_1** and **12_2** can be used jointly to obtain radiation on 2 frequency bands, as per the requirements of a GNSS system and without the need for a complex excitation circuit (herein there is only one antenna access port). Such simplicity favors reducing the bulk and reduces manufacturing costs.

Generalization

FIG. 9 schematically shows that the dipoles **14** may be arranged differently than what was discussed herein above for a coupling therebetween.

The arrangements have been shown in a simplified manner in said figure in order to well understand the concept.

More precisely, six different arrangements are shown in the Figure, numbered in Roman numerals from I to VI.

The first arrangement I corresponds to the arrangement shown in FIG. 1 whereas the second arrangement II corresponds to the arrangement shown in FIG. 5. Such arrangements are only repeated in order to facilitate comparison with arrangements III to VI.

The third arrangement III proposes moving the access points **15** away so that the access points **15** no longer form

a square, but a rectangle. In such a case, the powered dipole **14A** and the first coupled dipole **14C1** have been separated in the second transverse direction **Y** from the second and third coupled dipoles **14C2** and **14C3**.

5 In the example of the fourth arrangement IV, a fourth coupled dipole **14C** is added so that the access points **15** form a regular pentagon.

In the example of the fifth arrangement V, the third coupled dipole **14C3** is removed so that the access points **15** 10 form an equilateral triangle.

15 The sixth arrangement VI corresponds to the same case as that of arrangement V except that the strands **16** and **18** are no longer rectilinear, but curvilinear. More generally, it is possible to envisage any shape for the strands **16** and **18**, in particular with meanders or folds, provided that the neighboring strands **16** and **18** are sufficiently close to provide coupling.

Thus, in each of the arrangements shown in FIG. 9, the access points **15** are arranged to form a polygon, the first 20 strand **16** of a dipole **14** extending along the second strand **18** of a neighboring dipole **14** on the polygon at a distance less than or equal to one tenth of the operating wavelength. In such case, the distance is defined as the minimum distance between two points of the two strands **16** and **18**.

25 By the expression "polygon", it should be understood here a non-flat polygon. This means that each coupled dipole **14C** is arranged so that each direction of one strand intersects a direction of another strand.

In this way it is possible to obtain an antenna **10** apt to 30 emit circularly polarized radio frequency waves and having a reduced bulk. Depending on particular cases, the polarization of the antenna **10** is an RHCP or LHCP polarization.

35 Thus, such an antenna is particularly suitable for multiple applications amongst which satellite positioning systems, whatever the nature thereof, digital satellite radio, communications with microsatellites in low orbit, RFID readers, radars or communication systems between vehicles.

It is also possible to envisage variants with a smaller 40 number of dipoles **14** in the antenna array **12**.

In particular, it is possible to consider a variant with two 45 dipoles, a powered dipole and a coupled dipole.

In this way it is possible to further reduce the bulk.

Two examples of embodiments (A and B) are given in FIG. 10.

45 In both cases, the strands of the dipoles **14** forms substantially a square.

According to the example of embodiment A, the strands of the dipoles **14** are straight.

By contrast, in the example of embodiment B, the strands 50 of the dipoles **14** form a bend.

More precisely, the strands comprises a first part and a second part, both parts being orthogonal and linked together.

The first parts are arranged similarly to the case of the strands of the dipoles **14** of the embodiment A. The second 55 parts are arranged so that the strands fold towards the other dipole.

Furthermore, the second parts are shorter than the first parts. Typically, the length of a second part is inferior to half the length of a first part.

60 According to a particular embodiment, the number of dipoles **14** in the antenna array **12** is higher, e.g. more than 5.

In this way, better quality circular polarization can be generated and more frequency bands can be addressed.

65 According to one embodiment, such performance is further improved by a symmetrical antenna pattern, i.e. the dipoles **14** are arranged symmetrically with respect to an

axis and the lines producing the feed are parallel to said axis, as is the case for the arrangement shown in FIG. 5 where the axis corresponds to a direction at 45°.

As explained hereinabove, it is possible to print the patterns on a rigid or flexible dielectric material, which facilitates the implementation of the antennas.

It can even be considered to print the antennas directly on the system equipped with the antenna.

Finally, in all the preceding embodiments, the antenna 10 is described as operating in transmission mode, yet the reader will understand that the arrangement of the antenna 10 can also be used for an antenna operating in reception mode.

For this purpose, it is sufficient to connect the powered dipole 14A to a receiver suitable for receiving a wave at the operating frequency f_0 instead of connecting the dipole to a source suitable for generating a wave at the operating frequency f_0 .

Thus, in the general case, a powered dipole 14A is connected at an access point 15 to a radio frequency transmitter suitable for generating or receiving a wave at the operating frequency f_0 .

The invention claimed is:

1. A radio frequency antenna including at least one antenna array operating at an operating frequency, each antenna array comprising:

a powered dipole, the powered dipole being connected at an access point to a radio frequency transmitter adapted to generate or receive a wave at the operating frequency,

at least one coupled dipole, each coupled dipole being connected in an access point to a respective load which is resistive and/or capacitive and/or inductive,

the powered dipole and each coupled dipole having two strands, the strands extending from the access point, the access points being arranged to form a polygon,

a direction being defined for each strand, the powered dipole and each coupled dipole being arranged so that each direction of one strand intersects a direction of another strand,

the first strand of a dipole extending along the second strand of a neighboring dipole on said polygon at a distance less than or equal to one tenth of the wavelength corresponding to the operating frequency, said wavelength being called operating length.

2. The radio frequency antenna according to claim 1, wherein the two strands have a length less than or equal to a quarter of the operating wavelength.

3. The radio frequency antenna according to claim 1, wherein the first strand of a dipole extends along the second strand of a neighboring dipole on said polygon at a distance less than or equal to one twentieth of the operating wavelength.

4. The radio frequency antenna according to claim 1, wherein the directions of the two strands of the same dipole have an angle therebetween equal to 90° within plus or minus 10%.

5. The radio frequency antenna according to claim 1, wherein the polygon is a regular polygon.

6. The radio frequency antenna according to claim 1, wherein the number of coupled dipoles of an antenna array is between 2 and 4.

7. The radio frequency antenna according to claim 1, wherein the radio frequency antenna includes first and second antenna arrays, the polygon formed by the access points of the second antenna array being included in the internal space delimited by the polygon formed by the access points of the first antenna array, each antenna array operating at a respective operating frequency.

8. A radio frequency antenna according to claim 1, wherein the radio frequency antenna has a reflector plane located at a distance less than or equal to one quarter of the operating wavelength.

9. A radio frequency antenna according to claim 1, wherein the strands have meanders or folds.

10. A radio frequency antenna according to claim 1, wherein the loads of the coupled dipoles are chosen so that: the radiation from the radio frequency antenna has a right circular polarization with a maximum gain along the direction perpendicular to the radio frequency antenna, the radiation from the radio frequency antenna has a uniform right circular polarization for an elevation aperture between 90° and -90° around the direction perpendicular to the radio frequency antenna, and the gain of the cross polarization is minimized.

11. A system including at least one radio frequency antenna according to claim 1.

12. A system according to claim 11, where the system is a satellite positioning system.
